UNITED STATES PATENT OFFICE.

ADOLPHUS D. GOODWIN, OF SALEM, VIRGINIA.

DESIGN FOR A WINDOW-LOCK.

SPECIFICATION forming part of Design No. 20,955, dated July 21, 1891.

Application filed May 14, 1891. Serial No. 392,777. Term of patent 7 years.

To all whom it may concern:

Be it known that I, ADOLPHUS D. GOODWIN, a citizen of the United States, and a resident of Salem, in the county of Roanoke and State of Virginia, have invented certain new and useful Improvements in Window-Locks; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a representation of the invention and is a perspective view, and Fig. 2 is a plan view.

This invention has relation to certain new and original designs for window-locks; and it consists in the novel form and configuration as herein described, and shown in the accompanying drawings.

The leading feature of the design consists in the oval or elliptical shape of the body, having transverse ridges on a portion of its peripheral edge, as hereinafter fully described.

In the drawings, A represents the body of the lock, having an approximately oval or elliptical form, as shown. One end of the

ellipse is contracted, as shown at *a*, and extended to form the double concave neck portion *b*, enlarged at its free end and having the form shown at *e*. The two sides of the ellipse are unevenly contracted, so that the concavity of one side of the neck portion is greater than that of the opposite side. 30

A portion of the peripheral edge of the elliptical body A is shown as having the transverse ridges or teeth *f*. The faces of the body portion may be hollowed out, as shown, forming the oval recess *h*, in the bottom wall 40 of which is a curved shoulder offset downwardly. To one side of this shoulder is shown a perforation *g*.

Having described this invention, what I claim, and desire to secure by Letters Patent, 45 is—

The design for window-locks having substantially the form herein shown and described.

In testimony whereof I affix my signature in 50 presence of two witnesses.

A. D. GOODWIN.
